UNITED STATES PATENT OFFICE.

LESLIE W. CLAYBOURN, OF MENASHA, WISCONSIN.

APPARATUS FOR CURVING PRINTING-PLATES.

1,372,064.

Specification of Letters Patent.

Patented Mar. 22, 1921.

Application filed April 2, 1919. Serial No. 286,945.

To all whom it may concern:

Be it known that I, LESLIE W. CLAYBOURN, a citizen of the United States, residing at Menasha, in the county of Winnebago and State of Wisconsin, have invented certain new and useful Improvements in Apparatus for Curving Printing-Plates, of which the following is a specification.

My invention relates to apparatus for curving printing plates, and is especially useful for curving printing plates to be used in relations where it is desirable that the spacings between the printing lines of the printing plate when curved shall be the same as said spacings when said plate was in the flat, and is especially useful for curving printing plates employed in multi-color printing, in which a plurality of plates is employed for printing different colors, the impressions of which are intended to register with each other, and is also applicable in other relations where maintenance of relations of printing lines during curving of the printing plate is to be effected.

My present invention is an improvement on the apparatus shown, described and claimed in my application for patent on improvements in apparatus for curving printing plates, filed March 9th, 1917, Serial No. 153,731.

My invention consists in providing a plurality of mold-sections having surfaces about which a printing plate is capable of being curved, with means for moving said mold-sections whereby simultaneous movements of the same are insured; further, in novel means for connecting a flexible band about said mold-sections; further, in novel means for connecting the mold-sections so as to revolve together; further, in novel means for rolling the connected mold-sections; further, in novel related means for simultaneously and equidistantly revolving the mold-sections toward and from each other; and for rolling the mold-sections together; further, in novel means for gaging the printing plate and for pressing the printing plate during heating thereof; further, in novel operating means for said pressing means and positioning means; and, further, in novel relations of parts for cooling the mold-sections.

The invention will be further understood from the following description and claims, and from the drawings, in which latter:

Figure 1 is a front elevation of my im-

proved device, showing the mold-sections in separated relation and the presser engaging means raised.

Fig. 2 is a rear elevation of the same.

Fig. 3 is an end elevation of my improved device, showing the mold-sections in closed relation, with one end of the flexible band released.

Fig. 4 is a front elevation of my improved device, partly broken away, showing the mold-sections in connected relation adjacent to one end of the limits of rolling movement of the same.

Fig. 5 is a plan view of my improved device, showing the mold-sections in separated relation and the presser and gaging means raised and partly broken away.

Fig. 6 is a vertical longitudinal section of my improved device, partly broken away, taken on the line 6—6 of Fig. 5, showing the mold-sections in plate-contacting relation in the curving operation.

Fig. 7 is a plan view of the mold-sections in connected relation.

Fig. 8 is a central vertical cross-section of my improved device, taken on the line 8—8 of Fig. 5, showing the presser and gaging means in depressed positions.

Fig. 9 is an enlarged cross-sectional detail, showing the connecting means for the mold-sections and the hinging means for the flexible band, taken in section on the line 9—9 of Fig. 7.

Fig. 10 is a plan view of a printing plate about to be bent.

Fig. 11 is a longitudinal section of the same, taken on the line 11—11 of Fig. 10.

Fig. 12 is a cross-section of the same, taken on the line 12—12 of Fig. 10 the back of the plate being provided with longitudinal depressions.

Fig. 13 is a central longitudinal section of the bent plate as the same is received off the bending molds, taken on a line corresponding to the line 11—11 of Fig. 10, the backing of the plate being provided with cross ribs.

Fig. 14 is a sectional detail of the trunnion connections of one of the mold-sections, taken on the line 14—14 of Fig. 1.

Fig. 15 is an axial section of the operating means, taken on the line 15—15 of Fig. 1.

on the line 18—18 of Fig. 2, showing the adjusting means for one of the presser feet.

Fig. 19 is an axial section of the arresting means for the mold-sections, taken on the line 19—19 of Fig. 1; and,

Fig. 20 is a perspective view in detail of the latching means for the presser arms.

The method of curving the printing plate herein shown and described, is more fully

10 shown and described and is claimed in my co-pending application, Serial No. 145,881, filed February 1, 1917; the printing plate formed by the said method and by the apparatus herein shown, described and claimed, 15 is more fully shown and described and is claimed in my co-pending application, Serial No. 153,782, filed March 9, 1917; and the heating means herein shown and described, are more fully shown and described and are 20 claimed in my co-pending application Serial No. 153,753, filed March 9, 1917.

The printing plate to be curved is exemplified at 21. It is first formed flat, as shown in Figs. 10, 11 and 12. It is provided 25 with a printing surface 22. It may be formed in any ordinary or usual manner and be, for instance, an electroplate, in which case it comprises a printing shell 23 of electro-deposited metal, having a higher fusing 30 point, and a backing 24 of metal or material having a lower fusing point, the shell and backing being rigidly connected, all as more fully shown, described and claimed in my aforesaid applications. Printing plates constructed in other manner, as by stereotyping, or other methods, may also be curved by my 35 improved apparatus.

The margins of the printing plate are 40 preferably provided with bearers 25, 26, separated from the printing surface by grooves 27, 28, the bearers 25 being exemplified as at the ends of the printing plate, representing its top and bottom when secured to the plate-cylinder in the printing press, the bearers 26 45 being exemplified as the side bearers. The bearers are useful for receiving the edge thrusts and the margin portions of the surface-contacts in the curving of the printing plate for protecting the printing surface.

50 If desired, the rear face of the backing of the printing plate may be provided with recurrent depressions 29, forming ribs 30. The depressions and ribs are shown in Fig. 12, as extending lengthwise of the curvature of the 55 printing plate, and in Fig. 13 as extending crosswise of said curvature.

My improved apparatus includes a table 31. A flexible band 32 is arranged to be supported on the table. This flexible band 60 may be a band of cold rolled steel. The printing plate is arranged to be supported by the flexible band, and, if desired, a cushioning layer 33, which may be a sheet of paper, may be interposed between the printing plate and the flexible band. The print-

ing plate is laid up-side-down upon the flexible band, the printing surface being presented to the cushioning layer, when said cushioning layer is employed.

It is the intention to curve the printing plate on a sector of a cylinder to conform substantially to the usual plate-cylinders to which curved printing plates are arranged to be attached by suitable well-known attaching means, allowance being made for 70 finishing the inner surface of the curved printing plate, as by shaving the same, so that the inner surface of the finished curved printing plate will conform to the curvature and diameter of the plate-cylinder of the 75 printing press on which the curved printing plate is to be secured.

In the present exemplification, a pluri-part mold is employed, about which the printing plate is curved, the printing plate 80 being located in a printing plate space 36, between the flexible band 32 and said mold, while subjecting the printing plate to the bending or curving operation. The mold-sections are exemplified at 37, 38.

The ends of the band are articulated by 85 hinges 41, 42, to opposite ones of the mold-sections, at least one of the hinges being releasable.

The hinges 41 are located between the 90 mold-section 37 and a cross-strip 43, to which latter one end of the flexible band is secured. The hinges 42 comprise butts 44 extending outwardly from the mold-section 38, and butts 45 extending from a cross-strip 46 to which the other end of the flexible band is rigidly secured. A cross-strip 47 has 95 slidable connections with the cross-strip 46, as by means of headed bolts 48, received through slots 49 in the cross-strip 47, and 100 threaded into the cross-strip 46. (See Figs. 7 and 9.)

Pintles 50 are secured to the cross-strip 47, and are arranged to slide in holes in the butts 45 and into holes in the butts 44, when 105 the mold-sections are in separated relation, the holes in the respective butts being brought into registry with each other when the mold-sections are in such separated relation. A cross-strip 51, fixed to the mold-section 38, has the butts 44 fixed thereto. A cross-strip 52, fixed to the mold-section 37, has the butts 53 of the hinges 41 fixed thereto, the other butts 54 thereof being fixed to the cross-strip 43.

A handle 55 is fixed to the cross-strip 47, for moving the latter, and operating the pintles 50 to connect or disconnect the hinge-parts of hinges 42.

The mold-sections are provided with arc-faces 61, which, when the mold-sections are brought together, are continuations of one another for forming a composite mold having a bending face formed as a sector of a cylinder as hereinbefore described.

The curving of the printing plate is effected progressively along the curvature in lines parallel with the axis of the curvature equi-distantly from the median line of the plate parallel with said axis. Excess pressure upon the plate perpendicular to its printing surface is also preferably avoided.

For effecting these purposes, the respective mold-sections are provided with gear-segments 62, 63, these gear-segments being at the respective ends of the respective mold-sections. The gear-segments mesh with toothed racks 64, 65, on the machine frame 66. The coactions between the gear-segments and the toothed racks insure maintainance of parallelism between the mold-sections during movements of the latter; insure that the proper distance between the hinges 41, 42, as well as proper relative movements between flexible band and the mold-sections, are maintained; and insure proper spacing between the flexible band and the arc-faces of the mold-sections, this latter spacing being preferably approximately the thickness of the printing plate plus the cushioning layer 33, when the cushioning layer is employed.

Bearers 68, 69, are provided for the mold-sections, the bearers 68 being shown on the mold-sections and the bearers 69 at the respective edges of the table, the bearers having the purpose of insuring the proper height of the printing plate space 36 between the arc faces of the mold-sections and the flexible band, aided by the coaction between the gear-segments and toothed racks.

In order to maintain the mold-sections in proper relative positions when connected, pins 71 on the respective mold-sections are arranged to be received in holes 72 on the opposite mold-sections. Latches 73 are secured to a rod 74, rockable on one of the mold-sections. The latches are arranged to be received over lugs 75 on the other mold-section. The latches are normally resiliently urged into range with the lugs by means of springs 76, in order to automatically lock the mold-sections together when moved to full extent toward one another. The closing of the mold-sections may be aided by handles 77, 78, fixed to the respective mold-sections, as on the cross-strips 52, 51. A handle 79 is secured to the cross-rod 74 for releasing the latches when it is desired to separate the mold-sections. (See Figs. 7 and 9.)

Novel means are provided for moving the mold-sections simultaneously and equidistantly toward and from each other, and for rolling the mold-sections together when the same have been connected. This is accomplished in the present exemplification by providing the respective mold-sections with trunnions 84, 85, the axes of which are coincident when the mold-sections are in connected relation. The trunnions are respectively located on extensions 86, 87, on the respective mold-sections received in recesses 88, 89, in the opposite mold-sections. (See Figs 1, 2, 3, 4, 5, 6 and 14.)

Explaining the present exemplification more particularly, and referring to Fig. 5, which illustrates the mold-sections in separated relation, the left-hand mold-section is provided with the extension 86 and the right-hand mold-section is provided with the extension 87, these extensions being at opposite ends of the respective mold-sections. The right-hand mold-section is provided with the recess 88, at the same end of the pair of mold-sections at which the extension 86 is located. The left-hand mold-section is provided with the recess 89 at the same end of the pair of mold-sections at which the extension 87 is located. When now the mold-sections are connected, the extension 86 is received in the recess 88, and the extension 87 is received in the recess 89, with the axes of rotation of the trunnions 84, 85, on the respective extensions 86, 87, (see also Figs. 1 and 2), coincident with each other, such a relation being shown in Fig. 4, in which the axis of rotation of the trunnion 84 at one end of the pair of mold-sections is coincident with the axis of rotation of the trunnion 85 at the other end of the pair of mold-sections, these trunnions being located in the bearings 92, 94. (See Figs. 7 and 14.)

A slide 91 has the bearing 92 for the trunnion 84 extending from the mold-section 37, and a slide 93 is provided with the bearing 94 for the trunnion 85 extending from the mold-section 38. The slides respectively coact with guides 96, 97. The slide 91 is provided with rollers 98, coacting with guide 96, and the slide 93 is provided with rollers 99 coacting with guide 97. The relations of the guides, slides and trunnions is preferably such that the axes of the trunnions and of the rollers at the respective sides of the machine are located at the angles of a triangle so that tilting of the slides is avoided.

A flexible connection 101, exemplified as a sprocket-chain connects with the slide 91, and a flexible connection 102, exemplified as a sprocket-chain, connects with the slide 93.

The sprocket-chain 101 is received loopwise about sprocket-wheels 105, 106, and the sprocket-chain 102 is received loopwise about the sprocket-wheels 107, 108. The sprocket-wheels 106, 108, are loose on a shaft 110 journaled in bearings 111 on the frame. The sprocket-wheel 105 is fixed to a shaft 114 journaled in bearings 115, 116, on the frame. The sprocket-wheel 107 is arranged to be fixed to or to be loose on a shaft 117, journaled in bearings 118, 119, on the frame.

Bevel-gears 121, 122, are fixed respectively to the shafts 114, 117. An intermediate bevel-gear 123, meshes with the respective bevel-gears 121, 122. The intermediate bevel-gear is journaled about a stud-shaft 124 fixed in the frame.

An operating handle 126 extends from a hub 127 about the shaft 114. The hub is arranged to be fixed to the shaft 114, as by means of a set-screw 128, threaded in the threaded bore of a lug 129 on the hub 127 and received in a socket 130 in the hub of the sprocket-wheel 105, for causing the handle, the sprocket-wheel 105, the shaft 114, 15 and the bevel-gear 121 to be rocked together.

The sprocket-wheel 107 is arranged to be selectively fixed to the shaft 117, or to be released therefrom, by a clutch 134, arranged to be operated by a fork 135, on a lever 136, pivoted to the frame at 137, and having a cross-rod 138 articulated therewith at 139, the cross-rod being provided with a handle 140 for operating the clutch, the cross-rod being provided with suitable notches 141, arranged to be selectively received about a stirrup 142, to place the clutch 134 in connected or disconnected relation with the sprocket-wheel 107. (See Figs. 2, 3, 5, 16 and 17.)

30 The clutch is shown as a tooth-clutch comprising a collar 145 having spline connection 146 with the shaft 117, and having but one tooth 147 arranged to be received in the one coacting notch 148 in the sprocket-wheel 107, to insure that the connected relation of the shaft 117 with the sprocket-wheel 107 shall be at the point to insure proper relative movements between the mold-sections. As shown, a part revolution of the 35 sprocket-wheels is sufficient to insure the maximum desired revolutions of the separated or connected mold-sections. The tooth is arranged to be received in the notch at the point of connected relation of the 40 mold-sections. A collar 149 holds sprocket wheel 107 in place.

When the sprocket-wheel 107 is secured to its shaft 117, and the operating handle 126 is operated, reverse rotations are imparted to the sprocket-wheels 105, 107, by means of the cross-shafts 114, 117, through the medium of the bevel-gears 121, 123, 122, thereby moving the sprocket-chains in opposite directions, and causing movements of 55 the respective slides 91, 93, in opposite directions, for rolling the mold-sections 37, 38, in opposite directions simultaneously and equidistantly. When the operating handle is moved in one direction, the mold-sections are caused to approach each other, and when the operating handle is moved in the opposite direction the mold-sections are caused to move away from each other.

60 When the mold-sections are moved toward each other until they are brought into con-

nected relation, and it is desired to roll the connected mold-sections above the table, the clutch 134 is released, whereby the sprocket-wheel 107 is loose on its shaft. The sprocket-wheels 106, 108, 107, are therefore 70 idle sprocket-wheels during such relation.

The movement of the operating handle is communicated to the sprocket-wheel 105, for operating the sprocket-chain 101, whereby the slide 91 having connection with said 75 sprocket-chain is operated, the movement of the slide being communicated to the connected mold-sections for rolling the connected mold-sections above the table, parallelism of the mold-sections during the rolling 80 motion being maintained by reason of the gear-connections between the segment-gears of the mold-sections and the toothed racks at the respective ends of the connected mold-sections, the slides aiding in maintaining this parallelism. The sprocket-chain 102 moves idly over the idle sprocket-wheels 108, 107.

During the rolling of the connected mold-sections the printing plate is pressed in the 90 printing-plate space 36 between the flexible band and the mold-sections to press the printing plate against the curved faces of the mold-sections and correct any unevenness 95 of curvature.

It is desirable to fix the mold-sections in separated relation while gaging and pressing the printing plate, as hereinafter described, to prevent movement of the mold-sections toward each other while the gaging means or 100 pressing means are in operative positions. For this purpose I provide a locking pin 151 pivoted to a hand-lever 152 and located in a hole 153 of the frame. The lever is pivoted at 154 to a lug of the frame. The pin is 10 arranged to be pushed into a hole 155 in the sprocket-wheel to prevent movement of the slides, the hole 155 being so positioned as to lock the mold-sections in separated relation. The heel 156 of the lever is arranged to strike the frame to hold the pin in the hole 153. (See Figs. 1, 3 and 19.)

The printing plate is preferably heated prior to being bent, to render the backing readily flowable under pressure, the heating 11 being preferably to such a degree and throughout such period of time as will effect a spongy condition of the backing material, that is, a heat condition in the backing material which is near its point of fusion: 11

This may be accomplished in the bending machine, for which purpose the table 31 is represented as partially immersed in a bath 161, in a melting pot 162, the table being supported and positioned in the pot in suitable manner as on suitable blocks 163. The heat for the melting pot may be provided by suitable gas-burners 164, comprising suitable gas and air mixers 165, valves 166 regulating the temperature applied to the melt- 12

ing pot. The pot is positioned by lugs 160 on the frame.

The bath 161 is preferably of a material which, when cold, is a solid, and having a fusing point somewhat similar to the fusing point of the backing material of the printing plate, and is rendered fluid by the heat to which the melting pot is subjected, all as more fully shown and described in my afore-10 said applications. The heat is transmitted to the printing plate through the table 31, the flexible band 32, and the cushioning layer 33, if the latter be employed.

The printing plate is preferably subjected 15 to pressure during application of heat, in such manner as to bear the plate upon the heat-transmitting part uniformly throughout its extent to insure uniform distribution of heat throughout the plate. Thus presser-20 feet 170 extend from slide-blocks 171, adjustable lengthwise of arms 172, and held in adjusted positions by set-screws 173. The arms are adjustable laterally by being provided with bearings 174, adjustable length-25 wise of a rock-shaft 175, and bearings 167 adjustable lengthwise of a rod 168 fixed to arms 169 fixed to the rock-shaft. The rock-shaft is journaled in bearings 176 on brackets 177 extending from the frame of the ma-30 chine. The bearings 174 are fixed to the rock-shaft in adjusted positions by means of set-bolts 178. The rock-shaft 175 and rod 168 are parallel, and the bearings 174 and 167 on the respective arms 172 are received 35 about said rock-shaft and rod to maintain the arms 172 parallel with each other. The arms and presser-feet are positioned so that preferably the majority of the presser-feet rest upon the rear faces of the printing plate 40 opposite the bearers 25, 26, when pressing the printing plate.

The arms are held in down position by being provided with latches 179, arranged to engage the latching edge 180 of a rocker-bar 181, rockable in bearings 182 on the frame, and operated by a handle 183 thereon to release the latches. (See Figs. 1, 4, 5 and 20.) The latches are in the form of levers pivoted on pins 184 on the arms, and are 50 spring-pressed by means of spring 185 to engage the rocker-bar. A spring 186 normally holds the latching edge 180 of the rocker-bar in latching relation. Lugs 187, 188, normally hold the latches and rocker-bar in latching relation.

When a plate of large area is operated on it is advisable to provide additional presser elements, said additional presser elements being preferably of greater area than the 60 area of the presser-feet 170 in order to contact a greater area of the backing to limit indentation by the presser elements when the backing is in heated condition.

The latter pressers may, for instance, be 65 presser-shoes 190, at the lower ends of

presser-stems 191, adjustable up and down in bearings 192 of slide-blocks 193, adjustable lengthwise of a selective one or ones of the arms 172, and fixed in adjusted positions by set-screws 194. (See Figs. 1, 2, 3, 5, 8 and 18.) The respective stems are adjustable in the bearings by means of a hand-wheel 195 journaled in the bearing 192 of the block, and held in the bearing to prevent endwise movement thereof by a screw 196, the inner 75 end of which is received in an annular slot 197 in the hand-wheel. The hand-wheel has a threaded bore 198 in which the threaded portion 199 of the stem is received. A screw 189 received in a slot in stem 191 prevents 80 turning of the stem. The adjustment is provided to exert more or less pressure by the shoes relative to the pressure exerted by the feet. The additional presser elements of greater area are intended to be employed to 85 exert pressure upon the inner portions of the backing of the printing plate, that is, within the lines of the bearers 25, 26, supplementing such of the presser-feet 170 as may be located to press upon the backing within 90 the lines of said bearers.

The arms 172 are provided with rearward extensions 201 having counterweights 202 thereon for normally retracting the arms out of the paths of the mold-sections. The re-95 traction may be cushioned by a spring 203 extending between an arm 204 secured to the rock-shaft 175 and the frame, the spring being located about a rod 200 articulated with said arm, between a collar 208 on said rod 100 and a bearing 209 on the frame through which said rod slides.

The printing plate is desirably so positioned with relation to the bending elements that contact between the bending elements 105 and the respective end edges of the printing plate will be simultaneously effected along lines parallel with the axis of curvature of the printing plate when curved, which axis is either parallel with or perpendicular to the 110 upright position of the printing lines indicated at 205, on the printing plate, so that when the curved printing plate is arranged upon the plate-cylinder of the printing press, the printing face will be upright upon 115 the printed sheet. For accomplishing this the said edges, representing the top and the bottom edges 206 of the printing plate, have been trimmed parallel with each other and with the axis of the plate, and the side edges 120 207 of the printing plate have been trimmed perpendicular to the edges 206.

In order to position the printing plate equidistantly from the respective mold-sections and in the middle of the table, gages 125 210 are provided, the gages being adjustable toward the front and rear on arms 211 and held in adjusted positions by set-screws 212, the arms 211 being adjustable laterally by having their bearings 213 adjustable length- 130

wise of a rod 214 and fixed in adjusted positions by set-screws 215. The rod 214 is fixed to arms 216 having bearings 217 about the rock-shaft 175.

- 5 One of the arms 172 is provided with a latch 220, pivoted thereto on a pivot 221, in such relation to the rod 214 that, when the arms 172 are depressed, the latch will automatically be received about the rod 214, so 10 as to cause the gages 210 to rise with the arms 172. (See Figs. 2 and 8.) If it is desired to place gages 210 in gaging position, the arms 172 are depressed, and release of the latch 220 effected, for instance, by means 15 of a pull-rod 222, having articulation with the latch at 223, and supported in eyes 224 on one of the arms. The arms 172 being allowed to rise, the gages remain in position on the bending band for the gaging operation. A collar 225 and spring 228 position the pull-rod.

The back of the printing plate is provided with a mark 226, which coincides with the median line of the printing plate. The 25 bending band is provided with a centering mark 227, with which the mark 226 is brought into registry. (See Fig. 5.) The gages 210 having been adjusted and lowered into gaging relation with the printing plate, 30 the side edge of the printing plate is guided against the gages, whereby the axis of the printing plate, when curved, is brought into parallelism with the axes of the mold-sections.

- 35 The presser means are then caused to descend to bear upon the plate. This is accomplished in the present exemplification by providing rock-shaft 175 with an arm 231. A link 232 is articulated with the arm at 233 40 and with a bell-crank lever 234 at 235. The bell-crank lever is pivoted on a stud-shaft 236 extending from the frame. A treadle-lever 237, in the form of a bell-crank, is pivoted to the frame on a stud-shaft 238, and is 45 provided with a treadle-arm 239. A link 242 is articulated at 243 with the bell-crank lever 234 and at 244 with the treadle-lever.

When the treadle-lever is depressed, the 50 arm 231 is caused to descend, thereby causing the arms 172 to descend, for the pressing relation of the pressers thereon with the printing plate, the latches 179 engaging the rocker-bar 181. When the printing plate has been properly heated, the hand-lever 55 183 is operated for rocking the rocker-bar 181 and releasing the latches 179, whereupon the counterweights cause the arms 172 to rise, carrying with them the gages 210 and the parts on which the same are 60 mounted.

Approach between the mold-sections now 65 being caused in manner hereinbefore described, the first contact between mold-sections and the printing plate is made simultaneously with the opposite ends of the

printing plate, as indicated in Fig. 6, such contact with said ends pinching said ends between the mold-sections and the flexible band sufficiently to maintain the ends of the printing plate at its printing surface against 70 separation, forming limiting means for preventing separation between the ends of said plate, the movement of the mold-sections toward each other continuing until the flexible band and the printing plate thereon are 75 curved about and upon the mold-sections, the inner faces of the mold-sections meeting, and the mold-sections being secured together by the latches 73 for forming a unitary mold, for instance, as exemplified 80 in Figs. 3, 4 and 7. This movement of the mold-sections to curve the printing plate is preferably a uniform and comparatively rapid movement.

Upon the curving of the printing plate 85 being accomplished, it is preferably subjected to pressure, accomplished by rolling the united mold-sections back and forth upon the table, whereby the printing plate is rolled between the flexible band and the 90 connected mold-sections to insure a uniform conformity of the inner face of the printing plate with the curvature of the mold.

Means are provided for subjecting the 95 printing plate being formed to the action of a cooling agency, applied at the inner face of the curved printing plate and acting thence outwardly, so as to set the inner or back portion of the printing plate in advance of the portion nearer the outer or 100 printing surface. The cooling is exemplified as accomplished by means of a body 247 of fluid, for instance, water, in each of the mold-sections, which are formed hollow for the purpose, the water being fed into the 105 mold-sections by inlet-pipes 248, with which hose 249 connect by means of couplings 250, the water being received from the mold-sections by outlet-pipes 253. Outlet hose 254 connect with the outlet-pipes by couplings 255. The flow may be regulated by suitable valves not shown, whereby the temperature of the fluid in the mold-sections 110 may be regulated.

The mold-sections are provided with co-acting contact-faces 258, 259, which coact with each other when the mold-sections are in connected relation. The upper portions of the mold-sections are provided with recesses 261, 262, intermediate of their ends, 115 in which the respective inlet and outlet pipes and hose are received, the hose extending upwardly and provided with sufficient slack portions so that the inner ends of the hose will readily follow the movements back and forth of the mold-sections and of the connected molds. The hoses are arranged to lie across cross-strips 51 and 52, so as to aid in guiding the ends thereof and prevent the kinking of the hose.

In the present exemplification of the method, the heated backing element is preferably in a compressible condition at the time of bending, being, for instance, spongy, due to the heat application, that is, readily flowable under pressure with relation to the printing shell. The printing shell retains its dimensions during the curving operation, so that the printing surface of the completed curved printing plate is the same as the printing surface before the curving. The spacings between printed lines are maintained, so that a printed impression taken from the plate after being curved is the same as a printed impression taken from the printing surface when in the flat, differently expressed, the printing surface of the curved printing plate laid out in plane is of the same dimensions as the printing surface when flat. A stretching of the printing surface during curving is avoided.

The material of the backing accommodates itself to the curvature, the molecules thereof undergoing rearrangement due to the character of the heating and curving action in the present exemplification, resulting in a curved printing plate in which the metal is not buckled or strained, so that the inner face of the curved printing plate lies snugly throughout its area against the peripheries of the plate-cylinder, without hollow spots thereunder.

Thus referring to Fig. 10, the ends of the plate are perpendicular to the plane of its printing face. When the plate has been curved, these ends are radial to the sector of the cylinder formed by the plate. (See Fig. 13).

When the curving of the printing plate has been accomplished, the bearers 25, 26, are trimmed from the plate, for instance, in the line of the grooves 27, 28, between said bearers and the printing surface. The ends of the plate are then provided with suitable attaching faces for securing the plate to the plate-cylinder, as more fully shown and described in my aforesaid applications.

The bearers 69 are shown as located on the front and rear walls of the machine frame. The table is shown adjustable with relation to the bearers 69 to insure continued parallelism between the supporting surface of the table and the bearers, and proper distance between the supporting surface of the table and the curved surface of the mold-sections. Thus adjusting bolts 266 are adjustable in cross-braces 267 of the machine frame, and held in adjusted positions by jam-nuts 268. (See Figs. 6 and 8.) The melting pot is supported on these adjusting bolts, the table being supported on the blocks 163 in the melting pot.

The trunnions 84, 85, may be held endwise in the bearings 92, 94. This is accomplished

(see Fig. 14) by having one end of the respective bearings bear against an end-face 270 on the respective mold-sections, a disk 271 fixed to the trunnion by a bolt 272 bearing against the other end of the bearing. This aids in the positioning and correct movement of the mold-sections.

Having thus fully described my invention, what I claim as new and desire to secure by Letters Patent, is:

1. In a machine for curving printing plates, the combination of mold-sections having surfaces about which a printing plate is capable of being curved, bending means arranged to be received about said mold-sections, operating means removed from said mold-sections, and driving connections between said operating means and said mold-sections to selectively move said mold-sections in opposite directions or unitedly. 80

2. In a machine for curving printing plates, the combination of mold-sections having surfaces about which a printing plate is capable of being curved, bending means arranged to be received about said mold-sections, and a plurality of stationarily positioned operating means for said mold-sections, said plurality of operating means arranged to move in opposite directions or in similar directions, whereby to selectively move said mold-sections in opposite directions or unitedly. 95

3. In a machine for curving printing plates, the combination of mold-sections having surfaces about which a printing plate is capable of being curved, bending means arranged to be received about said mold-sections, operating means for said mold-sections, connecting means connecting with said respective mold-sections, and means selectively connecting one or more of said connecting means with said operating means. 100

4. In a machine for curving printing plates, the combination of mold-sections having surfaces about which a printing plate is capable of being curved, bending means arranged to be received about said mold-sections, flexible connections respectively connecting with said respective mold-sections, and operating means selectively driving said flexible connections in opposite directions or causing movement thereof in similar directions. 110

5. In a machine for curving printing plates, the combination of means including a mold composed of a plurality of sections having curved peripheries and arranged for contacting opposite ends of a plate to be curved, means whereby to cause simultaneous revolutions equidistantly of said sections toward one another, and means for wrapping said printing plate about the mold-sections. 125

6. In an apparatus for curving printing 130

- plates, the combination of a flexible band arranged to receive a printing plate to be bent thereon, mold-sections having surfaces about which a printing plate is capable of 5 being curved, connections connecting said mold-sections and said band, there being a printing-plate space between said band and said mold-sections located between said connections, and means having connection with 10 said respective mold-sections whereby to cause simultaneous revolving movement of said mold-sections toward one another, whereby the band with the printing plate to be curved is bent about said mold-sections.
- 15 7. In a machine for curving printing plates, the combination of a flexible band, a pair of mold-sections having surfaces capable of having a printing plate curved thereabout, between which and said band the 20 printing plate to be curved is received, and means having connections with both said mold-sections whereby to cause said mold-sections to simultaneously revolvingly move toward each other and said band to be 25 wrapped progressively from both sides of its middle in equal proportions toward its middle about said mold-sections.
8. In a machine for curving printing plates, the combination of a flexible band, 30 mold-sections having surfaces capable of having a printing plate curved thereabout between which and said band the printing plate to be curved is received, a slide for each of said mold-sections, said mold-sections having journal connections with said slides, means for simultaneously moving said slides in opposite directions for causing simultaneous revolutions of said mold-sections in opposite directions, and means for 35 40 causing said slides to move in similar directions for unitedly rolling said mold-sections.
9. In a machine for curving printing plates, the combination of a flexible band, mold-sections having surfaces capable of 45 having a printing plate curved thereabout between which and said band the band the printing plate to be curved is arranged to be received, and geared means having connections with said mold-sections causing 50 simultaneous revolving movements of said mold-sections in opposite directions, whereby said band is wrapped progressively simultaneously from both sides of its middle toward its middle about said mold-sections, 55 said last-named means including means for unitedly rolling said band and mold-sections.
10. In an apparatus of the character described, the combination of a flexible band, 60 mold-sections coacting with said band, bearing means for said mold-sections whereby a printing plate space is formed between said band and said mold-sections, slides coacting with said respective mold-sections for roll- 65 ing the same, means for moving said slides

in opposite directions for simultaneously rolling said mold-sections in opposite directions, means for connecting said mold-sections to roll together, and means for causing said slides to move in unison with said connected mold-sections to unitedly roll the latter. 70

11. In an apparatus of the character described, the combination of a flexible band, 75 mold-sections coacting with said band, bearing means for said mold-sections whereby a printing plate space is formed between said band and said mold-sections, slides coacting with said respective mold-sections for rolling the same, means for moving said slides in opposite directions for simultaneously 80 rolling said mold-sections in opposite directions, means for connecting said mold-sections to roll together, means for causing said slides to move in unison with said connected 85 mold-sections to unitedly roll the latter, and means to maintain said mold-sections parallel. 90

12. In an apparatus of the character described, the combination of mold-sections 90 having surfaces about which a printing plate is capable of being curved, gear-segments on said mold-sections, toothed racks with which said gear-segments coact, slides for said respective mold-sections slidable 95 lengthwise of said racks, means for simultaneously moving said slides in opposite directions to roll said mold-sections toward one another to connect the same, and connecting means between said mold-sections, 100 said mold-section rolling means comprising means to roll said connected mold-sections. 105

13. In an apparatus of the character described, the combination of a pair of coacting mold-sections having surfaces capable of 110 having a printing plate curved thereabout, a pair of slides coacting with said respective mold-sections, a flexible connection coacting with each of said slides, means for simultaneously moving said flexible connections 115 in opposite directions for simultaneously revolving said mold-sections in opposite directions, and power shifting means whereby to cause said mold-sections to revolve together in united relation. 115

14. In a machine for curving printing plates, the combination of a flexible band, mold-sections having curved surfaces between which and said band the plate to be curved is arranged to be received, means 120 whereby to revolvingly move said sections toward each other to place said mold-sections in connected relations, said connected mold-sections having a recess between them, and means for cooling said respective mold-sections comprising cooling means having connections in said recess with said respective mold-sections. 125

15. In a machine for curving printing plates, the combination of a flexible band, 130

- 5 mold-sections having curved surfaces between which and said band the plate to be curved is arranged to be received, means whereby to revolvingly move said sections 5 toward each other to place said mold-sections in connected relations, said connected mold-sections having a recess between them, means for cooling said respective mold-sections comprising cooling means having connections in said recess with said respective mold-sections, said cooling means comprising flexible hose and cross-strips adjacent to the peripheries of said respective mold-sections for guiding said hose.
- 10 16. In a machine for curving printing plates, the combination of a flexible band, mold-sections having curved surfaces between which and said band the plate to be curved is arranged to be received, means whereby to revolvingly move said sections toward each other to place said mold-sections in connected relations, said connected mold-sections having a recess between them, connecting means between said mold-sections in said recess for connecting said mold-sections, and cooling means connecting in said recess with said respective mold-sections.
- 15 17. In a machine for curving printing plates, the combination of a plurality of mold-sections having curved surfaces, a flexible band having articulations at its respective ends with said respective mold-sections, said articulations comprising hinges including butts respectively on one of said mold-sections and said flexible band, a slide, hinge-pintles on said slide, and means for moving said slide lengthwise of the axis of said mold-section for connecting said butts respectively on said mold-section and said flexible band.
- 20 18. In an apparatus for curving printing plates, the combination of a flexible band, mold-sections coacting with said band, said mold-sections having surfaces capable of having a printing plate curved thereabout by means of said band, gear-segments on said mold-sections, coacting toothed racks therefor, a slide for each of said mold-sections having articulation therewith to roll the same, sprocket-chains connecting with said respective slides, means for driving said sprocket-chains including sprocket-wheels, shafts for the latter, and a clutch, means for rotating said shafts in opposite directions whereby to roll said mold-sections in opposite directions, connecting means for connecting said mold-sections, and means having connection with said clutch to release the same whereby to roll said connected mold-sections in unison.
- 25 19. In a machine for curving printing plates, the combination of mold-sections arranged to be separated for the reception of the printing plate to be curved, a flexible band having connections with said respective mold-sections between which and said mold-sections the printing plate to be curved is received, and means for pressing the printing plate toward said band comprising arms, presser-means adjustable thereon, a rock-shaft, a rod spaced from and parallel with said rock-shaft and rockable therewith, said respective arms provided with bearings about said rock-shaft and said rod, said bearings slidable lengthwise of said rock-shaft and rod whereby to laterally adjust said arms, and means for clamping said arms in adjusted positions.
- 30 20. In a machine for curving printing plates, the combination of a flexible band, mold-sections arranged to be separated for the reception above said flexible band of the printing plate to be curved, adjustable gaging means for positioning the printing plate to be curved in the space between said separated mold-sections, presser-means for pressing said printing plate in said space, and means between said presser-means and said gaging means to selectively connect the same for combined movement or for movement of one of said means independent of the other of said means.
- 35 21. In a machine for curving printing plates, the combination of a flexible band arranged to receive the printing plate to be curved, normally separated mold-sections with which said flexible band has connections, said flexible band arranged for bending a printing plate to be curved about said mold-sections, movable gaging means between said mold-sections for gaging the position of the printing plate to be curved with relation to said flexible band and separated mold-sections, movable presser-means arranged to press the printing plate to be curved toward said flexible band, means whereby said presser-means are moved out of the paths of said mold-sections, means for connecting said movable gaging means and said movable presser-means for causing said gaging means and said presser-means to move together, means for releasing said last-named connection, and means having combined connections with said mold-sections whereby said mold-sections are caused to approach each other for wrapping said flexible band and printing plate to be curved about said mold-sections.
- 40 22. In a machine for curving printing plates, the combination of a flexible band arranged to receive the printing plate to be curved, normally separated mold-sections with which said flexible band has connections, said flexible band arranged for bending a printing plate to be curved about said mold-sections, movable gaging means for gaging the position of the printing plate to be curved with relation to said flexible

band and separated mold-sections, movable presser-means arranged to press said printing plate to be curved toward said flexible band, means between said gaging means and said presser means to selectively connect the same for combined movement or for movement of one of said means independent of the other of said means, treadle means to move said gaging means and presser means 10 into the space between the mold-sections,

and means to automatically raise said connected presser-means and gaging means out of said space.

In testimony whereof, I have hereunto signed my name in the presence of two subscribing witnesses.

LESLIE W. CLAYBOURN.
